[57] CLAIM

The ornamental design for children's play sprinkler or the like, substantially as shown and described.

DESCRIPTION

FIG. 1 is a front elevational view of a children's play
sprinkler or the like showing our new design;

FIG. 2 is a rear elevational view of FIG. 1;

FIG. 3 is a side elevational view of FIG. 1;

FIG. 4 is a side elevational view taken from the side

FIG. 5 is a top view of FIG. 1; and

FIG. 6 is a bottom view of FIG. 1.
